FLOOR COVERING UNIT

Michele Pompili, Milan, Italy, assignor to Pirelli, Società per Azioni, Milan, Italy

Filed Jan. 6, 1967, Ser. No. 5,333

Claims priority, application Italy July 23, 1966

Term of patent 14 years

(Cl. D13—1)

Fig. 1

Fig. 2

FIG. 1 is a top plan view of my new design for a floor covering unit;

FIG. 2 is a side elevational view thereof; and

FIG. 3 is an end elevational view of the same.

The back of the floor covering unit is conventionally plain.

I claim:

The ornamental design for a floor covering unit, as shown and described.
